US0D1000035S

(12) **United States Design Patent** (10) **Patent No.:** **US D1,000,035 S**
(45) **Date of Patent:** **** Oct. 3, 2023**

(54) **KABOB PET TREAT**
(71) Applicant: **Spectrum Brands, Inc.**, Middleton, WI (US)
(72) Inventors: **Gregory van Eyk**, Christiansburg, VA (US); **Tiffany Dawn Potter**, Pearisburg, VA (US); **Victoria Gray Kendrick**, Boones Mill, VA (US)
(73) Assignee: **Spectrum Brands, Inc.**, Middleton, WI (US)
(**) Term: **15 Years**
(21) Appl. No.: **29/866,569**
(22) Filed: **Sep. 19, 2022**
